COMBINED MOP BUCKET AND STRAINER THEREFOR

William J. James, Calgary, Alberta, Canada

Filed Dec. 16, 1968, Ser. No. 14,989

Term of patent 14 years

Int. Cl. D7—99

U.S. Cl. D49—29

FIG. 1 is an isometric view of a combined mop bucket and strainer therefor, showing my new design;

FIG. 2 is a side elevation thereof;

FIG. 3 is an end elevation as seen in the direction of line 3—3 in FIG. 2;

FIG. 4 is an end elevation as seen in the direction of line 4—4 in FIG. 2; and

FIG. 5 is a fragmentary vertical sectional view, taken in the plane of the line 5—5 in FIG. 1.

The bucket handle shown in FIG. 1 has been omitted in FIGS. 2—5 for convenience of illustration.

I claim:

The design for a combined mop bucket and strainer therefor, as shown and described.
